UNITED STATES PATENT OFFICE.

STEPHEN H. BLODGETT, OF LINCOLN, MASSACHUSETTS.

RECEPTACLE.

1,126,364.

Specification of Letters Patent.

Patented Jan. 26, 1915.

Application filed June 13, 1912. Serial No. 703,873.

To all whom it may concern:

Be it known that I, STEPHEN H. BLODGETT, a citizen of the United States, residing at Lincoln, county of Middlesex, State of Massachusetts, have invented a certain new and useful Improvement in Receptacles, of which the following is a specification, reference being had therein to the accompanying drawings.

10 My invention relates to paper receptacles of the type made from a narrow strip or ribbon of card-board spirally wound to form the sides or walls of the receptacle and a bottom consisting of a disk of card-board. 15 These receptacles are intended particularly for use as cuspidors and the like, where cheap receptacles which can be burned or otherwise destroyed are required. Heretofore, in receptacles of the kind described, it 20 has been customary to support the bottom upon an additional coil or coils of the ribbon superposed on the inside bottom edge of the conical wall of the receptacle. This has been objectionable because the bottom 25 has been raised above the lower edge of the receptacle a distance equal to the full width of the ribbon employed; also because the bottom is readily displaced by any blow on the under side, and because the joint between the bottom and the side wall of the 30 receptacle is not usually water tight and this has necessitated filling the joint with some suitable material such as glue.

The paper receptacle embodying my invention is so constructed that the bottom can be located at a distance from the bottom edge of the side wall equal to one-half the width of the ribbon employed in making the receptacle, and this distance may be less, if desired. I accomplish this result by splitting a portion of the ribbon longitudinally and by inserting the bottom in the slit between the two halves of the ribbon. The bottom of the receptacle embodying my invention is therefore held firmly in place and cannot be displaced by being pushed in either direction. The joint between the edge of the bottom and the walls of the receptacle is also invariably tight, and does not require to be filled with glue or the like, thus saving an expensive hand operation. Furthermore, the receptacle embodying the present invention is especially adapted to be constructed by machinery.

55 The invention will be fully understood

from the following description taken in connection with the accompanying drawings, and the novel features will be pointed out and clearly defined at the close of the specification.

Figure 1 is a view in perspective of a cuspidor embodying my invention. Fig. 2 is a side elevation thereof. Fig. 3 is a vertical section on a somewhat enlarged scale.

Referring to the drawings, there is 60 shown at A, the ribbon from which the receptacle is constructed. At B, is shown the bottom which is a circular disk cut from card-board or other suitable material. The receptacle is made by spirally winding the 65 ribbon of card-board over a form or mandrel of suitable shape, suitable adhesive being applied to the overlapping portion of the ribbon as the ribbon is wound. In practice the ribbon is usually made to overlap a 70 distance equal to about one-half its width. The winding of the ribbon is begun at the bottom, and the ribbon is first split for a distance equal to two coils or turns. This portion is then wound in superposed coils 75 on the mandrel with the edge of the bottom entering the slit in the paper and glue being applied to the opposing faces of the ribbon of card-board as it is wound. After the two turns or coils of slit ribbon have 80 been wound on the mandrel, at least one turn or coil of the unslit ribbon is wound on, being applied in such position as to overlap exactly the two previous coils. Thereafter the winding of the unsplit portion of 85 the ribbon is continued spirally until a receptacle of the desired height has been formed.

While a single turn or coil of the split ribbon is all that is absolutely necessary to 90 support the bottom, I prefer to use two or more coils because this affords a wider ledge for the bottom to rest on, and therefore produces a stronger and more certainly waterproof receptacle. The construction will be 95 plainly seen from Fig. 3 where the upper and lower halves of the first coil of the split portion of the ribbon A are shown at a and b respectively while the corresponding portions of the second coil are shown at c and d. 100 It will be seen that the bottom B projects between the portions a and b, and c and d. Outside of this there is superposed a layer e, the first spiral layer being shown at g and the second at h. The split portions b and d 105

of the strip *b* which lie above the bottom make a watertight joint between the bottom and the sides of the receptacle without the application of an additional coating of glue 5 or the like.

What I claim is:

1. A receptacle composed of spirally wound ribbon and a bottom, a portion of the spirally wound ribbon at the bottom of the 10 receptacle being split, and the edge of the bottom of the receptacle being received between the two halves of the split portion of the ribbon.

2. An improved receptacle comprising 15 sides composed of ribbon spirally wound and a bottom, the lower portion of said ribbon being split for a length of at least one

coil, the bottom being received within the said split in the said ribbon.

3. An improved receptacle comprising 20 sides composed of ribbon spirally wound and a bottom, the lower portion of said ribbon being split for a length of at least one coil, the bottom being received within the 25 said split in the said ribbon, there being a coil of the unsplit portion of the ribbon overlying said split portion.

In testimony whereof I affix my signature, in presence of two witnesses.

STEPHEN H. BLODGETT.
